(57) **CLAIM**

The ornamental design for a travel bag interior, as shown and described.

DESCRIPTION

FIG. 1 is a perspective view of a travel bag interior showing my new design;

FIG. 2 is perspective view of the travel bag interior in FIG. 1 from the same angle in FIG. 1 shown without the clothing environment; and,

FIG. 3 is a top plan view of the travel bag interior in FIG. 1 shown without the clothing environment.

The broken line showing the environment is for illustrative purposes only and forms no part of the claimed design.
